Francis J. Rigney, Jr., Tiburon, Calif.

Application October 9, 1952, Serial No. 21,767

Term of patent 14 years

(CL. D34—5)

To all whom it may concern:

Be it known that I, Francis J. Rigney, Jr., a citizen of the United States of America, residing at Box 636, Main Street, Tiburon, California, have invented a new, original, and ornamental Design for a Game Board, of which the following is a specification, reference being had to the accompanying drawing, forming a part thereof.

The single figure of the drawing is a top plan view of a game board, showing my new design.

The game board is of conventional thickness.

I claim:

The ornamental design for a game board, as shown and described.

FRANCIS J. RIGNEY, JR.
